His Attorney.

UNITED STATES PATENT OFFICE.

EDWARD R. BERRY, OF MELDEN, MASSACHUSETTS, ASSIGNOR TO GENERAL ELECTRIC COMPANY, A CORPORATION OF NEW YORK.

METAL TUBING.

Application filed June 6, 1923. Serial No. 643,786.

The present invention relates to the manufacture of metal tubing.

It is the object of my invention to provide a convenient method of making metal tubes which are seamless and may be made extremely thin-walled if so desired.

In accordance therewith the desired metal, for example, copper, is deposited upon a core of silica, or quartz, from which the resulting tube may be removed when expanded thermally or otherwise. As moderate heating causes much greater expansion of the metal than of the silica core it furnishes a convenient method of rendering the shell and core separable.

The accompanying drawings illustrate the steps of carrying out my invention, Fig. 1 illustrating the core or mandrel before deposition of the metal; Fig. 2 the core coated 20 preliminary to the electrolysis with conducting material; Figs. 3 and 4 show the deposit built up by electrolysis; and Fig. 5 illustrates the finished article.

The mandrel or core 1, consisting of fused 25 quartz and having a smooth surface, first is provided with a conductive base 2 (Fig. 2) consisting for example, of a thin film of silver which may be deposited on the core by one of the processes used in the manufacture of mirrors.

Copper or other desired metal is deposited 30 by electrolysis on the base 2 to desired thickness, as shown in Fig. 3. The finished tube 3 finally is removed from the core at a temperature of about 300° C., or the metal may be mechanically expanded by burnishing, which allows the tube to be easily removed 35 from the mandrel. Due to the great difference in thermal coefficient of expansion of

quartz and metals, such as copper or silver, the core is easily removable from the shell. Although the drawing shows a cylindrical tube of uniform diameter, the invention obviously is not limited to the manufacture of tubes of this particular shape.

What I claim as new and desire to secure by Letters Patent of the United States, is:—

1. The method of making metal tubing which consists in electro-depositing the desired metal on a silica support and removing 50 said support at a sufficiently high temperature to cause separation of said members due to difference in thermal expansion.

2. A mandrel constituted of vitreous silica for the fabrication of metal tubing by deposition of metal thereon.

3. The method of making metal tubing which comprises electroplating metal onto a support having a coefficient of expansion which is low compared with the coefficient 60 of expansion of the deposited metal, and heating the combined support and deposited metal to a temperature sufficiently high to permit separation of the holder and deposited metal.

4. The method of making metal tubing which comprises applying a metallic film to a non-conducting support having a coefficient of expansion which is low compared with the co-efficient of expansion of said 70 metallic film, electro-depositing metal onto said film, and heating the combined support and metal to a temperature sufficiently high to permit separation of the support and deposited metal.

In witness whereof I have hereunto set my hand this first day of June, 1923.

EDWARD R. BERRY.
